FIG.1.

Patented Oct. 28, 1913.

UNITED STATES PATENT OFFICE.

XAVIER DE SPIRLET, OF BRUSSELS, BELGIUM

MECHANICAL SYSTEM FOR ROASTING SULFUROUS ORES BY A CONTINUOUS PROCESS.

1,077,010.

Specification of Letters Patent.

Patented Oct. 28, 1913.

Application filed March 18, 1913. Serial No. 755,159.

To all whom it may concern:

Be it known that I, XAVIER DE SPIRLET, engineer, residing at 10 Avenue Rogier, Brussels, in the Kingdom of Belgium, have 5 invented a new and useful Mechanical System for Roasting Sulfurous Ores by a Continuous Process.

This invention is an improvement in or modification of that described in United 10 States Patent No. 979,349, of date December 20th, 1910. It has been found that in the construction shown in the said prior specification, owing to the high temperature required for the complete desulfurizing of the 15 blonde for instance, and also, when the furnace is used for roasting pyrites rich in sulfur, there easily takes place in the floors where the pyrite or the blonde falls in the center of the roasting hearth, an agglomeration 20 of the pyrite or of the blonde owing to the commencement of fusion which is chiefly due to a comparatively large quantity of excessively hot ore concentrating temporarily on a comparatively small surface. 25

The drawback can be easily reduced or done away with, by modifying the arrangement of the furnace, and the object of the 30 present invention is to do away with this drawback.

A construction according to this invention is illustrated, by way of example, in the accompanying drawing, in which:

Figure 1 is a section on line 1—1 of Fig. 35 2 certain parts being shown in elevation, of a roasting furnace with one hearth, that is to say, with one stationary and one movable disk or plate. Fig. 2 is a horizontal section on line 2—2 of Fig. 1, and Fig. 3 is a partial detail showing a modified form of teeth 40 and ventilating passages for said teeth and roof.

In the said construction, the disks or plates *a* *b*, instead of being circular, are 45 annular.

In the example of a single floor furnace shown in Fig. 1, the annular plate *a*, on the bottom face of which are arranged the teeth *d* used for stirring the ore roasted on the 50 bottom plate *b*, is stationary. This disk *a* is supported outside by a series of columns *e* arranged at the corners of a polygon surrounding the furnace. It is also supported inside by columns *f* similar to the preceding ones and arranged at the corners of a poly-

gon in the central hollow space *c* of the furnaces.

The columns *e* support on arms or brackets *g* a circular outside rolling track *h*. The columns *f* support on brackets *i* an 60 inner rolling track *j*. Rollers *k* *l*, the pins of which are respectively secured to the outer circle *m* and to the inner circle *n* of the roasting plate *b*, thus enable the said plate to roll on the two tracks *h* *j*. The said 65 plate is rotated by the engagement of the pinion *o* of the spindle *p* with a toothed rim *q* which surrounds all the rollers *k*.

The stationary plate *a* is provided with a hopper *r* for supplying the ore, near the 70 inner edge of the said plate. The plate *b* is provided with an opening for the fall of the roasted ore at *s* near its outer edge.

The teeth *d* secured in the ceiling of the arch of the stationary plate *a*, are refractory material, in the same way as the plate itself. These teeth are shaped and arranged so as to shift the ore from the center toward the periphery of the movable plate *b* where the discharge hole or holes *s* is 80 provided.

The heating of the furnace and the circulation of hot gases take place in any suitable manner. This circulation preferably takes place in the direction opposite to that 85 of the movement of the ore.

For certain ores, the roasting of which produces an excessively high temperature injurious to proper working and starts fusion which may clog the teeth, it may be 90 of importance to avoid the said excess of temperature. This invention provides means for obviating the drawback by cooling both the plates or roasting hearths and the teeth used for turning over, stirring and 95 shifting the ore. A circulation of cold air or gas is produced in conduits such as *t* provided in the bricks of the arch and in the teeth *d* of the same as shown in Fig. 3. When fixed or stationary hearths are 100 employed, there is no difficulty in bringing about such circulation. The circulation of air or gas thus heated during the passage through the said conduits, can be utilized for special purposes in the works treating 105 the ores. For the purpose of producing the said circulation, the ventilating space *c* can be used as a natural means.

The arrangement of the disks or plates in annular shape enables the furnace to be 110

given a very large roasting surface, without fear of drawbacks due to a want of stability caused by the use of a circular arch of an excessive diameter, as the arch in question must be always too much curved in a roasting furnace.

Having now particularly described and ascertained the nature of my said invention and in what manner the same is to be per-

10 formed, I declare that what I claim is:—

In a roasting furnace, a rotary annular hearth, a fixed annular roof above said

hearth, a series of teeth suspended from said roof, said roof and teeth being provided with ventilating passages arranged 15 to extend continuously through alternate portions of the roof and the teeth.

In testimony whereof I affix my signature in presence of two witnesses.

XAVIER de SPIRLET.
